UNITED STATES PATENT OFFICE.

ORSEMEUS G. DAVIS, OF LUDINGTON, MICHIGAN.

PRESERVING AND FREIGHT CAR.

SPECIFICATION forming part of Letters Patent No. 236,789, dated January 18, 1881.

Application filed March 3, 1880. (Model.)

To all whom it may concern:

Be it known that I, ORSEMEUS G. DAVIS, of the city of Ludington, in the county of Mason and State of Michigan, have invented certain new 5 and useful Improvements in Preserving-Cars and Freight-Cars; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my car, partly broken 15 away to show my improvements. Fig. 2 is a view of the stove and pipe, and Fig. 3 is a transverse sectional view of the car.

The nature of my invention relates to a car-body for preserving articles during transportation; and my improvement relates, essentially, to means for maintaining the air within the preserving-room of the car at a required temperature, as set forth in the following description, and pointed out in the claim.

In the drawings, A designates the car-body, and B its roof, which is provided with the usual center strip, C, and side guards, D. Upon the platform are arranged the ordinary guards E and any suitable or well-known 30 braking devices.

The car-body is divided into two compartments, one of which, G, is used as the stove-room, and the remaining compartment, H, as the preserving-room. The walls of the preserving-room are disposed as follows, so as to constitute a series of walls with spaces between them, to wit: A wall, I, is constructed within the car-body so as to leave a space, I', between the said wall I and the wall I² of the car-body. The opposing faces of the walls I I² are lined with zinc and the space between them filled with charcoal. The wall I is lined inside with heavy stiff paper, and an air-space, K, left between this wall and the next inner wall, L, which is also lined inside with like paper. An air-space, M, is also left between the wall L and the last inner wall, N, which last-named wall is lined with zinc upon its inner face. At the lower corners of the preserv-

ing-compartment are gutters or water-ways P, 50 to collect any water therein, and this may be carried by short pipes into the stove-room. The spaces between the aforesaid walls have ribbing R, and apertures R' are made through the paper and paper-lined walls, so that the 55 spaces between them will communicate. At the corners of said walls are angle-straps, which strengthen the structure.

It may here be observed that no bolts pass entirely through the walls, since the metal 60 thereof would communicate cold to the preserving-chamber.

The doors S, which open into the preserving-chamber, are formed with spaces similar to the above-described walls, and are formed 65 with beveled edges adapted to fit closely into the sills.

T designates the stove-pipe, from which a heating-pipe, U, extends into the preserving-room, and thence back again to the stove-pipe. 70 In the two branches of the pipe U, between the stove-pipe and the partition V, are valves V', both valves being controlled by a single stem, V². In the stove-pipe, between the arms of the pipe, is arranged a valve, U', the method 75 of heating the preserving-room being as follows:

The valve U' being closed and the valves V' opened, heat will pass into the pipe U, and thence back into the stove-pipe and up through 80 the flue, which extends up through the roof. When the valves V' are closed, however, and the valve in the stove-pipe opened, heat will be shut off from the pipe which leads into the preserving-room, and the heat will then pass 85 directly along the stove-pipe and up through the flue.

To determine the temperature of the preserving-room I provide a thermometer, W, at one end of the said room, which is visible 90 through an opening, W', having glass windows.

In summer ice may be used in the stove-room in lieu of a stove, and any suitable means employed for conducting the cold air into the 95 preserving-room. Suitable means will in such case also be provided for collecting such drippings as may occur in the stove-room. The

car-top will be provided with suitable pipes, W², for purposes of ventilation.

What I claim is—

In a car having a stove-room and a preserving-room, the pipe T, leading from the stove through the roof of the stove-room, and having the damper U' located between the connections with the pipe U, in combination with the pipe U, provided with dampers V' V'' upon the rod V², leading from the pipe T into the

preserving-room and returning therefrom to the pipe T, substantially as and for the purposes set forth.

In testimony that I claim the above I have hereunto subscribed my name in the presence 15 of two witnesses.

ORSEMU^S G. DAVIS.

Witnesses:

R. P. BISHOP,
GEORGE IRVINE.
